FASTENING DEVICE

Edward James Tripp, Hanham, Bristol, England,
assignor to Simmonds Development Corpora-
tion Limited, London, England

Application December 6, 1937, Serial No. 178,372
In Great Britain December 9, 1936

12 Claims. (Cl. 24—211)

This invention relates to an improved fastening device for the attachment of doors, panels, aircraft cowlings and other coverings to framework or other structural parts, so that such 5 coverings may be rapidly and efficiently detached therefrom and attached thereto.

In the specification of my British Letters Patent No. 361,963, I have described and claimed a fastening device in which a latch body in the 10 form of a casing adapted to extend plug-like into a socket or equivalent staple member contains a plunger carrying locking arms spring influenced to tend to extend through lateral openings in the casing into engagement with the staple member to secure the latch body thereto, the plunger being slidable axially in the casing in the direction in which it extends into the staple member to retract said locking arms against their 15 spring influence, and in the opposite direction to allow said arms to move under their spring influence to extend through the lateral openings in the casing. In the fastening device more particularly described in said specification, the locking arms are attached pivotally to the 20 plunger to rock about axes transversely of the latter from positions in which they extend away from the free end and longitudinally of the plunger, to positions in which they extend outwardly through the lateral openings in the casing; the edges of said locking arms being so 25 shaped as to co-operate cam-fashion with the margins of the corresponding lateral openings in the casing to effect their retraction and extension through said openings.

30 The improved fastening device according to the present invention comprises a casing which is attachable to a door or other covering, a plunger movable axially within said casing and spring influenced to extend outwardly, and a latch or locking arm which is retracted and 35 extended through an opening in the casing to its unlocked and locked position by the inner end of said latch or of an attachment thereto co-operating with one or more surfaces on the plunger and/or on the casing which are inclined obliquely to the direction of movement of the plunger, so that when the said plunger is pressed 40 inwardly into the casing, the latch is retracted within the casing, and, on release of the plunger, returns to its locking position.

In the present preferred form of the invention, the latch or locking arm is secured to a pin or cross-piece which extends transversely of said plunger and whose ends extend through slots in 45 arms or walls of the plunger and engage in slots

or grooves in walls of the casing, the said slots or grooves in the casing inclining inwardly away from said opening and transversely to the slots in the plunger which are so disposed that parts thereof register with the slots or grooves in the 5 casing for the various axial positions of the plunger.

One form of fastening device in accordance with this invention is illustrated in the accompanying drawing, in which

Figure 1 is a side elevation of the fastening device showing one mode of attachment to aircraft cowling,

Figure 2 is a sectional view of the fastening device, showing another mode of attachment to 15 aircraft cowling,

Figure 3 is a top plan view of the fastening device,

Figure 4 is a bottom plan view thereof, and

Figure 5 is a vertical sectional view to an enlarged scale, showing the device with the latch 20 fully retracted.

Referring to the drawing, the fastening device comprises the casing 1 which is open at both ends and which is provided at its outer end with a 25 flange 2 whereby it may be secured to a door, aircraft cowling or other covering, the said flange 2 being suitably formed with holes 3 for this purpose. Movable axially within the casing 1 is a 30 plunger which comprises the head portion 4 which slidably fits the casing 1, and two opposed operating walls or arms 5, which are provided with suitably inclined slots or apertures 6 to cause movement as hereinafter described to the pin 6 which extends transversely of the said 35 plunger and which has pivotally mounted thereon a latch or locking arm 7 that is urged to extend laterally into locking position through the aperture 8 provided in a wall 1' of the casing 1. Helical springs 11 formed with extensions, of 40 which one, 11', is anchored to the head portion 4 of the plunger, act to urge the plunger outwardly and thereby the latch or locking arm outwardly to its locking position. The other extension of the springs 11 engages the inner end 45 of the latch 7, thereby urging the latch inwardly against the inner edge of the opening 8.

The ends of the pin 6 engage in slots 10 which are formed in the walls of the casing adjacent the wall 1' and which extend transversely to the slots 50 9. The slots 10 incline inwardly away from the wall 1' of the casing, so that when the plunger is depressed against the action of the springs 11 which are thereby tensioned, the pin 6 is forced inwardly by the outer edge of the slots 9 to bear 55

against the inner edge of the slots 10 and to move therein away from the side 1' of the casing, the latch 7 being thereby drawn out of engagement with the latch plate or other member with which it engages to fasten the door or other covering. It will be seen that the latch or locking arm moves in a direction which is substantially at right angles to the direction of movement of the plunger.

10 A transversely-extending slot 12 or interiorly-disposed groove may be suitably formed in the side of the casing opposite the side 1' so that, when the latch is fully retracted, the adjacent edge portion of the head 4 of the plunger may be placed within such slot or groove, whereby the latch is held in its retracted position. In this position, the pin 6 and the arms 5 of the plunger have the positions shown in Figure 5 and in dotted lines in Figure 1. The springs 11, when 15 the plunger is depressed, urge the lower part of the plunger to pivot about the pin 6 away from the opening 8, so that when the edge portion of the head 4 registers with the slot 12, such edge portion is urged into the slot by the action of 20 the springs 11. When it is desired to release the plunger, it is given a small pivotal movement in the reverse direction to bring the edge of the head 4 of the plunger clear of the slot 12, when the springs 11 return the latch and plunger to 25 the position in which the latch is fully extended. In this position, the head 4 of the plunger is, as shown, preferably flush with the flange 2 on the casing. To facilitate pivotal movement of the plunger of the thumb or finger of the hand, the head 4 thereof may be provided with a groove 13 as shown in Figures 2 and 4.

The casing of the fastening device may extend plug-like into a socket or equivalent staple member secured to the framework or other structural part to which the door or other covering is to be removably secured, the outer edge of the latch or locking arm, when in its locking position, abutting against an inner edge of the socket and thus locking the door or like covering. For example, as shown in Figure 2, the casing whose flange 2 is secured to cowling 14, extends plug-like into the socket 15 which is fitted into a bracket 16 that is secured to the framework 17. It will be seen that any action tending to draw apart the attached parts when the latch is in its locking position does not result in any tendency for the latch to retract out of engagement with the socket 15. Alternatively, the latch of the fastening device may engage directly an abutment on the structural part to which the covering is to be attached. For example, as shown in Figure 1, the flange 2 of the casing may be secured to cowling 14', the latch 7 extending through and engaging directly an edge of an aperture in the structural part 18 to hold securely such part 18 to the cowling 14'. The fastening device, being free from parts substantially projecting beyond the exterior surface of the part to which it is attached, is particularly applicable to the attachment of cowling, inspection doors and other coverings in aircraft.

The inner and outer sides of the latch 7 advantageously converge towards its outer end, the outer side of the latch preferably being parallel or substantially parallel to the flange, as shown. In this manner, when the latch moves to its locking position, the outer side thereof moves towards the flange on the casing, thus drawing tightly together the two parts to be attached.

75 It will be understood that variations in the

constructional details of the fastening device above described may be made in accordance with this invention. For example, a plurality of latches may be secured to the pin 6, and the angles of inclination of the slots may be varied. Furthermore, slots inclined to the direction of movement of the plunger may be formed only in the plunger or in the casing. For example, the pin to which the latch is secured may extend through slots in the plunger which extend at right angles to the direction of movement of the plunger, the ends of the pin engaging inclined slots in the casing, or the pin may extend through inclined slots in the plunger, the slots in the casing with which the end of the pin engages extending laterally.

I claim:

1. A fastening device comprising a casing having an opening in a side thereof, a plunger mounted within said casing and movable longitudinally therein, a pin extending transversely of said plunger, a latch secured at an inner part thereof to said pin and adapted to extend through said opening, and cooperating surfaces on said plunger and casing engaged by said pin and operable to move said pin away from said opening when the plunger is moved towards one end of said casing and thereby retract the latch through said opening.

2. A fastening device comprising a casing having opposed side walls and a front wall with an opening therein, a plunger formed with opposed side walls mounted within said casing and movable longitudinally of said casing, a spring urging the plunger towards one end of said casing, a pin extending transversely of said plunger, a latch secured at an inner part thereof to said pin and adapted to extend through said opening, and cooperating surfaces on the opposed walls of the plunger and casing engaged by said pin, at least one pair of said co-operating surfaces being cam surfaces operable to move said pin away from said opening when the plunger is moved longitudinally of said casing against the action of said spring and thereby retract the latch through said opening.

3. A fastening device according to claim 2, wherein said co-operating surfaces are formed by slots in the opposed walls of the plunger and casing, said pin extending through the slots in said walls of the plunger and engaging the slots in the said walls of the casing.

4. A fastening device according to claim 2, wherein said surfaces on the opposed walls of the plunger are formed by slots therein which are inclined obliquely to the direction of movement of said plunger.

5. A fastening device comprising a casing having opposed side walls and a front wall formed with an opening therein, a plunger formed with opposed side walls mounted within said casing with such side walls extending substantially parallel to the said casing side walls, a spring urging the plunger towards the outer end of said casing, a pin which extends transversely of said plunger, a latch secured at its inner end to said pin and adapted to extend through said opening, and co-operating slots in the opposed walls of the plunger and of the casing, said pin extending through the slots in the plunger walls and engaging the slots in the casing side walls, at least one pair of said co-operating slots being cam slots operable to move said pin away from said opening when the plunger is moved inwardly of the

casing and thereby retract the latch through said opening.

6. A fastening device according to claim 5, wherein said slots in the plunger side walls extend obliquely to the direction of movement of said plunger, and the co-operating slots in said casing side walls extend obliquely to the direction of movement of said plunger and transversely of the slots in said plunger walls.

10 7. A fastening device according to claim 5, wherein said latch is pivotally secured to said pin and said spring is housed within the plunger and engages both the plunger and the latch, whereby the plunger is urged outwardly of said 15 casing and the latch is urged against the inner edge of said opening.

8. A fastening device according to claim 5, wherein said casing is formed with a rear wall having an abutment surface, and said spring is 20 housed within said plunger and acts both to urge the plunger outwardly of said casing and, on depression of the plunger to the position in which the latch is retracted, to urge part of the plunger into engagement with said abutment and thereby 25 hold the plunger in said position.

9. A fastening device comprising a casing having opposed side walls and a front wall formed with an opening therein, a plunger formed with opposed side walls mounted within said casing 30 with its said side walls extending substantially parallel to the casing side walls, slots in the opposed walls of said plunger inclined obliquely to the direction of movement of said plunger, a pin extending transversely of said plunger with 35 its end portions extending through the oblique slots in the plunger walls, a latch pivotally secured at its inner part to said pin, and surfaces on said opposed side walls of the casing engaged

by said end portions of the pin and co-operating with said slots in the plunger walls to move the pin away from said opening when the plunger is moved inwardly of said casing and thereby retract the latch through said opening.

5 10. A fastening device comprising a casing having an opening in a side thereof, a plunger formed with opposed arms movable axially within said casing, a pin extending transversely of said plunger, a latch pivotally secured to said pin 10 and adapted to extend through said opening, a spring housed between said plunger arms and acting both to urge the plunger outwardly of the casing and to urge the latch against the inner edge of said opening, and co-operating surfaces 15 on said plunger and casing engaged by said pin and operable to move the pin away from said opening when the plunger is pressed inwardly of the casing and thereby retract the latch through 20 said opening.

11. A fastening device according to claim 10, wherein said casing is formed with a transverse slot and said spring also acts to pivot the plunger about the said pin to bring part of the plunger into engagement with said transverse slot when 25 the plunger is moved inwardly of the casing to a position in which the latch is fully retracted and thereby hold the plunger in such position.

12. A fastening device according to claim 10, wherein the inner and outer sides of said latch 30 converge towards the outer end thereof, and the outer end of said casing is formed with an outwardly-extending lateral projection which cooperates with said latch when the latch is extended through said opening, to draw together 35 the parts to be attached.

EDWARD JAMES TRIPP.
